UNITED STATES PATENT OFFICE.

LOUIS RABINER, OF BROOKLYN, NEW YORK.

HEAD-GEAR.

No. 890,095.

Specification of Letters Patent.

Patented June 9, 1908.

Application filed December 22, 1906. Serial No. 349,056.

To all whom it may concern:

Be it known that I, LOUIS RABINER, citizen of the United States, residing at Brooklyn, in the county of Kings and State of New York, have invented certain new and useful Improvements in Head-Gear, of which the following is a specification.

The invention relates to head gear and has for its object the provision of a cap generally known as the golf-cap, embodying the feature of being adjustable whereby the same may be suited to any shape head. Or whereby it may be arranged to suit the taste of the wearer, in either the loose flat style or 15 with the crown standing upright.

The further object of this invention is that one is enabled to manufacture and market caps of a given design thus relieving the retail dealer of the necessity of keeping in 20 stock a large assortment of designs for the fitting of different shape heads, which is both expensive and room taking.

Another object is in so applying the adjusting means that it may constitute a feature of its ornamentation, and in no manner hinder its use by the wearer. In its application the use of buttons is entirely omitted and instead loops of the same material as the cap are employed.

30 In the drawings: Figure 1 is a top plan view. Fig. 2 is a side view of the same. Fig. 3 is a vertical transverse section. Fig. 4 is a front view. Fig. 5 is a modification in front elevation. Fig. 6 is a section of Fig. 5 with 35 the straps folded within, and Fig. 7 is a bottom plan view partly cut away.

Referring to the drawings by reference characters, 1 designates the body of the cap made up of sectors, and 2 the peak thereof. 40 To either side of the peak 2, or where its tapered edges are secured to the body 1, is a band made of two pieces 3 and 4 which extend to the back and are united midway of the body 1. The lower edge of this band 45 alines with and is united to the lower edge of the body portion 1 as indicated by numeral 5. The free-ends of the pieces comprising the band, or those parts which are just above the ears of the wearer, are tapered as at 6 into straps 7 and 8 which extend cross-wise of the head to approximately the opposite sides of the cap, one of said straps overlapping the other. The straps 7 and 8 are the means whereby the adjustment above referred to is accomplished. At the ends of the straps are loops 9 and 10 securely at-

tached thereto and of the same material. Each strap is adapted to pass through the loop of its opposite strap. Thus if the wearer have a round head he may readily shape the 60 hat to more comfortably fit thereto by drawing the loops 9 and 10 in opposite directions. By this operation the band sections 3 and 4, and consequently the sides of the body 1 are drawn somewhat erectly, to which position 65 it is held by the loops gathering the inner or wider portions of the straps 7 and 8; the loop of strap 7 gathering the wide part of strap 8, and vice versa. If the head of the wearer be what is termed a long head it is 70 necessary for him simply to move the loops 9 and 10 in the reverse direction to that just described. By this adjustment the body 1 of the cap is loosened thereby permitting the same to readily adapt itself to the shape of 75 the head. In any event it is more often a matter of taste with the wearer as to whether he will have the crown overhang and fasten to the peak by means of the usual fastener, or whether he desires to wear the crown in 80 full erect position. By properly regulating the cross straps 7 and 8 the cap may be made to conform to either of these positions. In the former instance by tightening the straps, and in the latter by loosening them. Since 85 the band sections 3 and 4 are united to the body 1 in only one place namely along the bottom edge, they may be used in stormy weather in the nature of ear muffs merely by inverting the same, the straps 7 and 8 serving 90 as the piece which goes under the chin.

In a modified form I have shown this invention applied to a "Tam O'Shanter", wherein the members 7' and 8' are used in the capacity of a holding strap which goes 95 under the chin of the wearer, the said members 7' and 8' being in this instance regulated to the necessary position by the adjusting loops 9' and 10' which are carried by the straps as in the golf-cap arrangement. 100 To each of the straps 7' and 8', and at points thereon adjacent the head band 11, are ear pieces or protectors 12 and 13 secured thereto in any suitable manner, the straps being of greater width at those points to enable this. 105

When it is desired to use the "Tam O'Shanter" without the chin strap and the ear protectors, the members 7' and 8' are folded within the crown 12 as shown in Fig. 6. In this case the loops 9' and 10' are so regulated as to obviate any tendency of the straps 7' and 8' to wrinkle, and thus allow a per-

fectly smooth interior for the head. So that there will be no disarrangement of the head band 11 in this latter case the straps 7' and 8' are fastened to the cap at the upper inner 5 edge of said head band 11 as indicated at 14.

It will be noted that in both the golf-cap and the "Tam O'Shanter" the principles of adjusting and holding the straps are exactly 10 the same, each strap carrying at its end a loop through which passes the opposite strap and vice versa.

What is claimed as new is:—

A cap of the character described, comprising a body portion having a band covering 15 the back and side portions thereof, and adapted to hold said portions in erect posi-

tion; said band terminating in straps adapted to overlap on the crown of the cap, said straps being of greater width adjacent the band and having loops at their ends, said 20 loops adapted to encircle the straps respectively, and gather their wider portions whereby the overhanging of the cap's sides may be regulated, said band and straps adapted to pass under the chin and cover the 25 ears.

In testimony whereof I affix my signature in presence of two witnesses.

LOUIS RABINER.
